[57] CLAIM

The ornamental design for a bottle, as shown and described.

DESCRIPTION

FIG. 1 is a perspective view of a bottle showing our new design;

FIG. 2 is a side elevational view, the opposite side being the same in appearance;

FIG. 3 is a top plan view;

FIG. 4 is an elevational view looking from the right of FIG. 2, the opposite side being the same in appearance; and

FIG. 5 is a fragmentary cross-sectional view taken along the plane of the line 5—5 of FIG. 4.

FIG.1

FIG. 2

FIG. 5

FIG. 3

FIG. 4
